TURE GUSTAF RENNERFELT, OF STOCKHOLM, SWEDEN.

STONE-CRUSHING MACHINE.

1,141,581.

Specification of Letters Patent. Patented June 1, 1915.

Application filed March 25, 1913. Serial No. 756,791.

To all whom it may concern:

Be it known that I, TURE GUSTAF RENNERFELT, a subject of the King of Sweden, and a resident of Stockholm, in the Kingdom of Sweden, have invented certain new and useful Improvements in Stone-Crushing Machines, of which the following is a specification.

My invention relates to improvements in a machine for crushing stones, ore, clinkers and similar material. The machine most frequently used for such purpose comprises a frame, a jaw journaled in the frame, a spring between the jaw and the frame and a toggle joint between the jaw and the frame arranged to be operated through a pitman from an eccentric formed on the driving shaft in such manner that the jaw is given a swinging motion adapted to cause the crushing of the stones between the jaw and the frame—this type of machine being known as the Blake crusher. Machines of this type are necessarily constructed so that the diameter of the eccentric is very large compared with its useful eccentric radius, and as a consequence the mechanical efficiency of the machine is low—frequently so low that more than one half of the power applied for driving the machine is lost in the three bearings of the eccentric. The eccentric becomes exposed to very high pressures which frequently cause excessive heating and wear of its journals and bearings, and sometimes even break the driving shaft. The ability of the said toggle joint, peculiar to the Blake crusher, to transmit pressure to the jaw depends on the angle between the two levers of the toggle joint in such way that this ability is greatest when said angle is at a maximum—*i. e.* when the levers stand most nearly to a straight line—but at that moment the crushing of the stones between the jaw and the frame is already accomplished, so that in fact the toggle joint stands in a position to apply its greatest force at the moment when the force is least required. At the moment when the greatest force is needed for crushing the large stones the angle between the levers is more acute, and consequently the force of the toggle joint diminished. Machines of this type also suffer from the fact that the ends of the two levers of the toggle joint are so located that it is difficult to supply them with the proper lubrication, this difficulty being especially serious since undue friction at those parts

may cause—especially if the spring is weak—a reversal of the normal direction of pressures upon the bearings of the eccentric. Since there is always some play in these bearings such reversals will cause shocks which are disagreeably noisy and greatly damage the bearings. Another drawback lies in the fact that machines of this type are generally not equipped with a satisfactory safety arrangement, so that some expensive part of the machine becomes broken by an accidental excessive overload. Such excessive overloads occur quite often, since the workmen handling or operating the machine use in their work sledgehammers and other uncrushable steel tools which accidentally drop between the jaws of the stone crusher in spite of reasonable care.

The object of my invention is to obviate the aforesaid difficulties and to provide a stone crusher of high mechanical efficiency, which shall be reliable in operation and require a comparatively small amount of driving power, in which the bearings shall not be liable to heat, and of which no part which is expensive or difficult to replace shall be broken in case of excessive overload. My improved stone crusher will also possess the advantages that it is of shorter length and smaller bulk than crushers of the above mentioned type, and by reason of its higher efficiency it will require a flywheel of comparatively small weight. These advantages are of importance, since such crushers must frequently be transported along rough country roads.

In order to gain the aforesaid objects I use in my improved stone crusher no toggle joint and no eccentric with small eccentric radius. I employ instead a mechanism comprising an unequal armed lever and a roller, together with means for swinging the lever back and forth, the lever being fulcrumed in the frame, and the roller placed so that it can roll back and forth between the free end of the jaw and the shorter arm of the lever.

My invention is illustrated in the accompanying drawings in which—

Figure 1 is a vertical sectional view of a stonecrusher made according to my invention. Fig. 2 is a side view of the lever as seen in the direction of the arrow in Fig. 1.

Referring to the drawings in detail 2 represents the frame of the crusher, and 3 a plate of hard material fastened to the frame and thus constituting a part of the frame.

4 represents another hard plate fastened to the jaw 5 which by means of the shaft 6 is journaled in the frame.

5 7 represents the lever, formed in two parts kept together by the hinge 8 and the bolts or rivets 9. The fulcrum of the lever is formed by a round steel bar 10 fastened to the lever by rivets 11 (Fig. 2). The bar 10 rests on a concave face formed in a block 10 12 mounted slidably in the frame so that its distance from the plate 3 may be varied by inserting between the block and the frame a filler 14 of suitable thickness. The top end of the lever is connected through 15 the pin 15 to one end of the link or connecting rod 16, the other end of which is journaled on the crank 17 of a shaft which is journaled in the frame between the jaw and the lever. The throw of the crank is shown 20 in Fig. 1 of about twice the diameter of the shaft, so that upon rotation of the crank-shaft the lever 7 will oscillate between the two positions shown in full drawn and in dotted lines. Both parts of the lever are 25 preferably cast of steel. The short arm of the lever is provided with a forged or rolled steel shoe 18 which has a convex face and is dovetailed into the casting. The roller 19, formed substantially as a cylinder of hard 30 steel or chilled cast iron, is placed loosely between the shoe 18 and the concave face 20 formed at the lower end of the jaw 5. A spring (or springs) 21 applied between the jaw and the frame serves to keep the jaw 35 in firm contact with the roller. The plate 22 fastened to the jaw serves to facilitate the introduction of the roller 19 to its proper place when the machine is assembled, but does not come into contact with the roller 40 during the operation of the machine. 23 represents an oilcup for lubricating the fulcrum of the lever, 24 is a sheet iron cover, and 25 a flywheel keyed to the driving shaft.

45 26, 27 represent wheels upon which the machine may be mounted to facilitate its transportation on a road. The upper and lower parts of the lever, kept together by the aforesaid hinge 8 and bolts 9, are separated by a gap 28, across which the stud 50 29 extends, being fastened in the upper part and pressing with its end against the lower part.

55 The machine operates in the following manner: Power is applied to the driving shaft in suitable manner for instance by a belt on the flywheel, and upon rotation of said shaft the lever is set into a swinging or oscillating motion, its upper end moving through a long distance back and forth, and its lower end below the fulcrum moving a much shorter distance by reason of the great ratio between the lengths of the two lever arms. The motion of the lever is transmitted through the roller to the jaw 60 which, being pivoted on the shaft 6, will

swing in the manner customary in a stone-crusher and break the stones which are dropped between the plates 3 and 4. During this operation the roller 19 will roll between the concave face 20 and the convex 70 face of the shoe 18, and no sliding friction will exist at the points of contact between the roller and said faces; for this reason the roller requires no lubricant. The bar 10, which constitutes the fulcrum of the lever, 75 is supported along its whole length upon the block 12, and is subjected merely to pressure and not to any bending moment. For this reason the diameter of the bar 10 may be comparatively small, which is important 80 because it is necessary for the efficient operation of the machine that the friction at the fulcrum of the lever shall be small enough to permit the springs 21 to swing the lever around its fulcrum so that the 85 pressures upon the pin 15 indicated by the arrow and upon the crank 17 shall never reverse their normal directions. This result can be accomplished with reasonably strong springs, even though the lever arm is quite 90 short, provided that the friction at the fulcrum is small, and in order to avoid this friction entirely I prefer in some cases to form the concavity in the block 12 with a radius of curvature which is greater than 95 the radius of the bar 10 so that said bar will have a rolling motion upon said concavity, and no sliding friction at all will exist at the fulcrum. In such cases it is 100 however necessary that the angular oscillation of the lever, or the ratio between the throw of the crank and the length of the longer lever arm, shall be limited to a certain value depending on the radius of curvature in the block and on the coefficient of 105 friction thereon in a manner which will be understood by those versed in the art. This construction with a rolling fulcrum is preferable in very large machines, but for smaller machines I prefer to have a greater 110 oscillation of the lever, and to keep the friction low at the fulcrum by means of good lubrication.

115 The radius of curvature of the concave face 20 should be large enough to permit the roller to roll without slipping, and small enough to keep the roller in its proper place. It will be noted that the bolts 9 are so located, that during the operation of the machine they will be subjected to tension. 120 Their combined sectional area is great enough to stand the strain due to normal operation, but they possess less relative strength than any other part of the machine, so that when the crusher is subjected to an 125 excessive overload, caused for instance by a sledgehammer between its jaws, the said bolts will be pulled off. The motion of the jaw and the lower part of the lever will then cease while the motion of the flywheel, the 130

crankshaft and the upper part of the lever will go on, until the driving power be disconnected. During this time the upper part of the lever is guided by the aforesaid hinge 8, so that it cannot strike against the jaw or the cover. By reason of the gap 28 the upper part of the lever will not strike against the lower part; the aforesaid stud 29 will receive the first blow and thereby 10 become upset compressed or crushed so that further shocks or blows will not occur.

I do not limit my claims to the details of construction shown in the drawings, since many modifications can be made therein and 15 still come within the scope of my invention. For instance the curvature of the shoe 18 is shown in the drawings such, that the ratio between the effective lever arms is nearly constant during the whole stroke of the lever, but it can evidently be so chosen that 20 this ratio is greater in the beginning than at the end of the stroke. I can also use a plurality of rollers instead of a single roller 19, or I can use balls instead of rollers. It is 25 also evident that the cylindrical bar 10 could belong to the block 12 and a concavity corresponding to such a bar could be formed in the lever. In some cases a shoe of rolled material may be applied to the face 20, and 30 all such modifications are intended to be covered by my claims.

From the foregoing it will be observed that the roller 19 is located between a convex surface on the lever 7 and a concave surface 35 on the jaw 5; and that the arrangement and relative dimensions may be such that the center of curvature of the said convex surface may be so located below the fulcrum that it will oscillate on both sides 40 of a vertical line passing through said fulcrum, so that the instantaneous leverage of the short arm of the lever 7 remains substantially constant, and therefore excessive and abnormal strains on the member 17 are 45 avoided.

It will be further observed that the center of curvature of the concave surface 20 and roller 17 are located on a substantially vertical line below the shaft 6, so that the roller 50 moves in substantially a straight line, and that it is located sufficiently low for a line passing through the centers of pressure on said roller to also pass through, or near, the lower ends of the jaw members 3 and 4. It 55 results from this structure that the strains on the shaft 6 can never reverse in direction which often occurs with disastrous results in other types of rock crushers. Again, the strains on the roller 19 are so great that it

wears rapidly if it is allowed to slide. By 60 the construction above, however, there is little tendency for it to move up and down, and it consequently rolls through the distances moved, thus causing it to wear round instead of flat. 65

Having thus described my invention, what I claim is:

1. The combination of a frame; a jaw provided with a concave surface journaled in the frame; a lever having a fulcrum in 70 the frame; said lever having a convex face; a roller mounted loosely between the said concave surface and the said convex face; and means for oscillating the lever; the center of curvature of the convex face being located substantially vertically below the fulcrum of the lever. 75

2. The combination of a frame; a jaw having a concave surface journaled in the frame; a lever fulcrumed in the frame; said 80 lever having a convex face; a roller held by friction between the said concave surface and the said convex face; and means for swinging the lever back and forth; the center of curvature of said concave surface as 85 well as said roller being located in a substantially vertical line passing through the journal of said jaw, whereby said roller may move in a substantially straight line passing through its centers of pressure. 90

3. The combination of a frame; a jaw having a concave surface journaled in the frame; a lever having a fulcrum in the frame; said lever having a convex face; a roller held by friction between the concave 95 surface of the jaw and the convex face of the lever; means for oscillating the lever; said roller being located near to the lower end of the jaw and substantially vertically under the journal, whereby a line passing 100 through the centers of pressure on the roller will also substantially pass through the lower end of the jaw.

4. The combination of a frame; a jaw having a concave surface journaled in the 105 frame; a lever having a convex face fulcrumed in the frame; a roller mounted loosely between the said concave surface and the said convex face; a plate secured to the jaw to facilitate the mounting of the roller; 110 and means for swinging the lever back and forth.

Signed at Stockholm Sweden this eleventh day of March, A. D. 1913.

TURE GUSTAF RENNERFELT.
